UNITED STATES PATENT OFFICE

166,006

COMBINED SEWING MACHINE CABINET AND SEAT

Harry A. Trumfio, Chicago, Ill.

Application March 7, 1950, Serial No. 8,374

Term of patent 14 years

(Cl. D33—12)

To all whom it may concern:

Be it known that I, Harry A. Trumfio, a citizen of the United States, residing at Chicago, in the county of Cook and State of Illinois, have invented a new, original, and ornamental Design for a Combined Sewing Machine Cabinet and Seat, of which the following is a specification, reference being had to the accompanying drawing, forming a part hereof.

In the drawing:

Figure 1 is a perspective view of a combined sewing machine cabinet and seat, embodying my new design.

Figure 2 is a perspective view of the combined sewing machine cabinet and seat, shown in the previous figure in the opened out or extended position.

Figure 3 is a perspective view of the seat shown in Figure 2, but showing the opposite side thereof.

The opposite side of the cabinet is like that shown and the back is plain.

I claim:

The ornamental design for a combined sewing machine cabinet and seat, substantially as shown and described.

HARRY A. TRUMFIO.
